UNITED STATES PATENT OFFICE.

LEWIS A. FOOTE, OF CHICAGO, ILLINOIS, ASSIGNOR TO CHICAGO CAR SEAL AND MANUFACTURING COMPANY, OF CHICAGO, ILLINOIS, A CORPORATION OF ILLINOIS.

SEAL.

SPECIFICATION forming part of Letters Patent No. 745,587, dated December 1, 1903.

Application filed March 18, 1903. Serial No. 148,367. (No model.)

To all whom it may concern:

Be it known that I, LEWIS A. FOOTE, a citizen of the United States, residing at Chicago, in the county of Cook and State of Illinois, ⁵ have invented a new and useful Improvement in Seals, of which the following is a specification.

My invention relates particularly to seals for use on cars and in analogous situations; ¹⁰ and my primary object is to provide a self-locking seal of simple and cheap construction and one which cannot be tampered with without ready detection.

The invention is illustrated in the accompanying drawings, in which—

Figure 1 represents a perspective view of the seal in the open condition; Fig. 2, a similar view of the seal in the closed or locked condition; Fig. 3, a perspective view illustrating the manner in which the parts of the seal are assembled; Fig. 4, an enlarged broken section taken as indicated at line 4 of Fig. 2; Fig. 5, a section taken as indicated at line 5 of Fig. 4; Fig. 6, a broken perspective ²⁵ view of a modification of the seal, and Fig. 7 a broken section taken as indicated at line 7 of Fig. 6.

In the construction shown in Figs. 1 to 5, inclusive, the seal comprises a tin or sheet-metal casing or body A, equipped interiorly with a locking member a, and a shackle A', having one end anchored in the casing and the other end equipped with a locking member a'. The casing comprises a side plate c, ³⁵ having its inner surface provided with depressions c' and having one curved end edge and curved lateral edges bounded by a flange c², the other end of the side plate being cut straight and left unflanged, as indicated at c³, and a side plate d, provided with one curved end edge and curved lateral edges and having the metal struck up to form at the inner surface a longitudinal channel or depression having portions d' d² of a given width and ⁴⁰ depth and an intermediate portion d³ of the same depth and constricted width and a portion d⁴ of the same width as the portion d³, but of less depth. The shackle A' has the metal struck down to form on its lateral side ⁴⁵ bosses f, which fit into the depressions c', and

has the metal struck up at its anchored extremity, as indicated at f', to afford beneath said struck-up portion a space for receiving the anchored end of the locking member a. The locking member a comprises a flat spring- ⁵⁵ metal member having one end turned under, as indicated at g, to fit into the space beneath the enlargement f' and having the other end bent back upon its upper surface and bifurcated to form locking-prongs g'. The prongs ⁶⁰ g' are separated by a slot g² and have oblique edge portions g³, terminating at the points of the prongs, which are turned away from each other. The locking member a' is formed by cutting away the metal of the shackle at the ⁶⁵ edges thereof near the free end of the shackle, as indicated at h, striking the metal up beyond the cut-away portions, as indicated at h', and bending it into substantially box form by turning it downwardly at the lateral margins ⁷⁰ 70 to form vertical portions h² and inwardly to form lower flanges h³. This affords a longitudinal channel h⁴, open at the extreme end of the shackle to receive the locking member a. The walls h² are cut away to form openings or slots h⁵, affording locking-shoulders ⁷⁵ for engaging the prongs of the locking member a. The rear ends of the flanges h³ are bent up beneath the raised portion h' to form a guard h⁷, preventing insertion of an instrument between the ends of the shackle in the locked condition. Adjacent to the neck of the shackle at the cut-away points h the metal is perforated and struck upwardly to form a raised eye h⁶. ⁸⁵

In assembling the parts the turned extremity g of the member a is hooked under the portion f' of the inner end of the shackle, and the shackle is then placed so that the bosses f engage the depressions c' of the plate c. The ⁹⁰ plate d is then put into place, fitting within the flanges of the plate c. In this position the raised portion d⁴ receives beneath it the raised portion f' of the shackle. The edges of the flange c are then turned over upon the ⁹⁵ edge margins of the plate d and locked, as indicated in Fig. 4. In this operation, or before, if desired, the plate d has a channel formed on its upper surface near its periphery for receiving the edge of the flange c². This ¹⁰⁰

channel is preferably formed by striking the metal downwardly to form a bead or rib h , and the member c is similarly beaded or ribbed, as indicated at h' . These beads or ribs may 5 be formed in the plates before the flange is bent over, if desired.

From the foregoing description it will be understood that the locking member a is anchored in such a manner that it is held centered in the channel d^3 , so that the box-form free end of the shackle may be slipped over the outer end of the locking member a to permit the prongs to enter the slots h^5 . The wide portion d^2 of the channel, with which the 15 member d is provided, affords space for the prongs of the locking member a , and the constricted portion d^3 prevents access to the prongs. Moreover, when the shackle is locked the neck portion at h fits into the portion d' of the channel, and the shoulders l aid in closing the entrance to the channel. Also the raised boss h^6 abuts against the struck-up portion of the metal adjacent to the channel d' , affording an additional safe- 25 guard against the insertion of any instrument and also affording a means of detection in case the shackle is broken off and shortened and then inserted into the casing. It will be understood, of course, that the 30 seals may be marked in any suitable manner and that they will commonly be numbered and arranged in numerical order for use. The perforation at h^6 affords a convenient means for arranging the seals on a wire 35 in numerical order.

In the modification shown in Figs. 6 and 7, B represents a cast-metal casing or body equipped with a locking member b , and B' a shackle having one end anchored in the casing. 40 The casing is formed with a longitudinal channel b' , in which the member b is centered. The inner end of the shackle has a struck-up portion b^2 , provided with a perforation b^3 , and the member b has its inner or 45 rear end turned downwardly to afford a hook b^4 , received by the slot b^5 and cast into the metal of the casing. This provides for the secure anchoring of both the shackle and the locking member. The locking member is of 50 the same construction as the locking member a , and the free end of the shackle is equipped with a locking member similar to the locking member a' .

In both constructions the inner locking 55 member is located so as to be free from tampering, and the shackle is so constructed that it cannot be altered without detection. This overcomes the objection inherent in certain seals which employ a hook on the end of the 60 shackle, which may be broken off and a new hook formed.

It will be understood that changes in details of construction within the spirit of my 65 invention may be made. Hence no undue limitation should be understood from the foregoing detailed description, which has been given for clearness of understanding only.

What I regard as new, and desire to secure by Letters Patent, is—

1. A seal, comprising a body formed with a 70 suitable longitudinal channel, a locking member comprising a sheet-metal member having its rear portion anchored in said body and its front portion bent upon itself and bifurcated to afford locking-prongs, said front portion 75 being suitably centered in said channel, and a shackle provided at its free extremity with a locking member having lateral walls for pressing said prongs together during insertion of the shackle and locking-shoulders for 80 engaging the extremities of said prongs, for the purpose set forth.

2. A seal, comprising a body having a suitable longitudinal channel, and a shackle and locking member having interlocking portions 85 anchored in said body, said locking member being centered in said channel and equipped with yielding locking-prongs and said shackle having at its free extremity a locking member adapted to fit over said first-named locking member and provided with locking-shoulders, for the purpose set forth.

3. A seal, comprising a plate having depressions on its inner surface formed by striking the metal outwardly, a shackle having 95 one end provided with bosses engaging said depressions, a locking member having one portion interlockingly engaging the inner end of said shackle, a second plate provided with a longitudinal channel and having flanged 100 connection with said first-named plate, and a locking member at the free end of said shackle, for the purpose set forth.

4. A seal, comprising a flanged plate having the metal struck outwardly to form depressions on its inner surface, a shackle having the metal struck downwardly to form bosses engaging said depressions and the metal struck upwardly at its extremity, a locking member having a hooked end engaging a 110 struck-up portion of said shackle, a second plate formed with a longitudinal channel in which said locking member is centered and which is secured to said first-named plate by said flange and a locking member at the free 115 end of said shackle, for the purpose set forth.

5. A seal, comprising a suitable body provided with a longitudinal channel, a shackle having one end anchored in said body, a locking member having its rear end portion anchored in said body and equipped at its free or outer end with rearwardly-turned prongs, and a locking member at the free extremity of said shackle having slotted lateral walls and of sufficient size to receive said first-named 125 locking member, for the purpose set forth.

6. A seal, comprising a suitable body equipped with a longitudinal channel, a shackle having one end anchored in said body, a locking member having one end anchored 130 in said body and equipped at its other end with locking-prongs, and a box-form locking member at the free end of said shackle and formed integrally therewith, the lateral walls

thereof being cut away to afford locking-shoulders for engaging said prongs, for the purpose set forth.

7. A seal, comprising a suitable body, an inner locking member, a shackle having one end anchored in said body, and a box-form locking member formed integrally with the other end of said shackle and provided with suitable locking-shoulders and shoulders adjacent to the inner end of said last-named locking member obstructing the entrance to the channel in said body.

8. A seal, comprising a suitable casing, a

locking member anchored therein, and a shackle having one end anchored in said casing and equipped at its free end with an integrally-formed locking member formed by bending the lateral edge margins of the shackle downwardly and inwardly at the extremity of the shackle, referring to the closed position of the shackle, for the purpose set forth.

LEWIS A. FOOTE.

In presence of—

A. C. KITTLESON,
WALTER N. WINBERG.
